HYDRAULIC PUMPING JACK

Ira Morgan White, Oakland, Calif., assignor to
 The Pelton Water Wheel Company, San Francisco, Calif., a corporation of California

Application October 30, 1945, Serial No. 625,502

6 Claims. (Cl. 60—52)

1

This invention relates in general to a hydraulic deep well pumping jack system including a hydraulic jack; a balancing pressure tank, a constant displacement pump and an automatic control valve. The balancing pressure tank of the system is maintained at a pressure such that the resulting lifting force of the pressure applied in the hydraulic jack would be equal to the rod weight plus one-half of the fluid weight normally lifted by the jack. The operating pump and control valve are disposed between the jack and the balancing tank so that operation of the pump and control valve to produce flow from the tank to the jack will lift the piston in the jacket while operation of the pump and control valve to produce flow from the jack to the tank will lower the piston in the jack. A special hydraulic control mechanism is provided to reverse automatically the action as the jack reaches the terminal point of each end of the stroke. By maintaining the pressure in the balancing tank as described above, the pump is subjected to a substantially constant load during the upstroke and downstroke of the jack. During the upstroke the pump must develop sufficient pressure which when applied to the jack will augment the balancing tank pressure and lift the entire rod plus the fluid load. Conversely, during the downstroke, the pump must sufficiently reduce the pressure within the jack so as to remove fluid from the jack so that the load on the jack will be reduced to the rod load only.

In addition to the normal operating devices required for the hydraulic pumping jack, the jack is provided with a safety feature in order to bring about shutdown of the jack in the event of rod breakage and consequent loss of load to the jack. If such a device were not provided, the pump would be subjected to excessive overdrive conditions in the event of loss of part of the load supported by the jack. For example, a rod breakage during the upstroke of the jack could reduce the load on the pump discharge to below the pump suction supplied by the balancing tank. This condition could possibly set about destructive forces if the rod breakage control device were not incorporated.

In general then, the object of this invention is the provision in a hydraulic pumping jack system of the character described, of means for protecting the system from damage by reason of abnormal operating conditions, such as sucker rod breakage.

More specifically, the object of this invention is the provision in a hydraulic pumping jack

2

system of the character described, of a normally open valve which will automatically close in response to predetermined sub-normal pressure in the jack.

5 The invention possesses other advantageous features, some of which with the foregoing will be set forth at length in the following description where that form of the invention, which has been selected for illustration in the drawings 10 accompanying and forming a part of the present specification, is outlined in full. In said drawings, one form of the invention is shown, but it is to be understood that it is not limited to such form, since the invention, as set forth 15 in the claims, may be embodied in a plurality of forms.

Referring to the drawings:

Fig. 1 diagrammatically illustrates a hydraulic pumping jack system embodying the objects of 20 my invention shown with the system in the upstroke portion of its cycle.

Fig. 2 is a view similar to Fig. 1 but showing the system in the downstroke portion of its cycle.

25 Fig. 3 is an enlarged detail longitudinal section of the automatic valve incorporated in the system to safeguard it due to any damage which might otherwise occur as a result of any abnormal differential pressures to which the system 30 might be subjected.

In general, the system shown in these figures 35 includes a hydraulic jack A, the piston of which carries a polished rod; a balanced pressure tank B, maintained at a pressure sufficient to produce plus one-half of the fluid load supported by the jack; a constant displacement pump C, capable of producing a pressure above the tank pressure sufficient to lift the rod weight plus the fluid 40 weight, and also capable of reducing the pressure in the jack below the pressure tank so as to permit the sucker rod to drop; a control valve D, disposed between the pump and the balanced pressure tank for alternately delivering fluid from 45 the pressure tank to the hydraulic jack on the upstroke of the jack and then from the jack to the tank on the downstroke of the jack; a pilot valve E, responsive differentially and hydraulically to the terminal movements of the hydraulic jack piston for operating the main control valve; and a shutoff valve F, for closing the circuit between the balanced pressure tank and the main control valve in response to any predetermined abnormal differential pressure existing in 50 the system.

As disclosed in Figs. 1 and 2, the hydraulic jack A includes a cylinder 1, with which is operatively associated a piston 2. Depending from the piston 2 through a suitable stuffing box in the lower end of the cylinder 1, is a polished rod 3, to which is fastened the sucker rod of an oil well pump. The cylinder 1 is provided on its lower end with a fluid operating medium inlet and outlet port 4 and at its upper end with a fluid outlet port 5 communicating through a check valve 6, line 7 and check valve 8 with an intake port 9 provided in the lower end of the cylinder above the port 4. Also provided on the upper end of the cylinder 1 are a pair of longitudinally spaced outlet drainage ports 11 and 12, communicating (through line 13, check valve 14, line 15, scavenging pump 16, line 17, check valve 18 and line 19) with an intake port 21 provided in the lower end of the balancing pressure tank B.

The pump C is of the constant displacement type, including a pair of opposed suction chambers 22 and 23 and a discharge compartment 24, and is adapted to be driven by any suitable power means. The suction chambers 22 and 23 are provided respectively with inlet ports 25 and 26 and the discharge compartment with a discharge outlet 27 and with a relief valve outlet 28 communicating through a relief valve 29 with an inlet port 31 associated with the suction chamber 23.

The main control valve D is of the piston type including a main cylinder 32 provided with five longitudinally spaced annular channels 33, 34, 35, 36 and 37. Provided on either end of the valve D, coaxially with the main cylinder 32, are smaller cylinders 38 and 39. Operatively associated with the main cylinder 32 are a pair of longitudinally spaced pistons 41 and 42 mounted on a piston shaft 43, and carried on the ends of the shaft 43 are pistons 44 and 45 operatively associated with the cylinders 38 and 39. The simultaneous movement of the pistons 41, 42, 44 and 45 from their positions as shown in Fig. 1 to the positions shown in Fig. 2 is effected through the pilot valve E in a manner which will be described later in connection with the description of the valve E. Communication between the lower end of the balanced pressure tank B and the annular channel 36 is established through the normally open port 46 of the shutoff valve F. Fluid from the balanced pressure tank B flows through the valve F, line 47 and port 36a into the annular channel 36. From this channel the fluid passes into the channel 37, through a port 37a associated with the channel 37 and through a line 48 and the inlet port 25 into the suction chamber 22. The line 48 communicates through a line 49 with a line 51 which, in turn, communicates with the inlet port 26 of the suction chamber 22 and with a port 38a associated with the annular chamber 38. It will, therefore, be seen that the fluid passing through the channels 36 and 37 of the main control valve will be delivered to both of the suction chambers 22 and 23 of the pump C. The pump C then delivers this fluid through its outlet port 27, through a line 52 and a port 35a associated with the channel 35 into the channel 35. From the channel 35, the fluid passes through the channel 34, through a port 34a associated with this channel and through a line 53 and the port 4, into the lower end of the cylinder 1. In this position the pump C operates to pass fluid from the tank B through the main control valve D into the lower end of the cylinder 1, thereby to raise the piston 2.

Any fluid which may have moved upwardly past the piston 2 is delivered through ports 11 and 12, line 13, check valve 14, line 15, scavenging pump 16, line 17, check valve 18, and line 19 through the port 21 associated with the lower end of the tank B into the tank B. In this connection, it should be noted that the scavenging pump 16 is operated so as to maintain substantially atmospheric pressure on the check valve 14.

When the piston 2 rises above the port 5, fluid under the main pump pressure passes through port 5, check valve 6, the upper portion of the line 7, and line 54 to the left end port 55 associated with the pilot valve E.

The pilot valve E is of the same type as the main control valve D, including a main cylinder 56 with which are operatively associated three longitudinally spaced coaxial pistons 57, 58 and 59, fastened to a common shaft 61. Formed on the right end of the pilot valve E is a cylinder 62 of a smaller diameter than the main cylinder 56 and which is provided with an outlet port 63. Operatively associated with the cylinder 62 is a piston 64, fastened to and forming a continuation of the right end of the shaft 61. Communication between the port 63 and the port 36b associated with the channel 36 of the main control valve D, is established by a line 65. With the main valve in the position as shown in Fig. 1, fluid from the tank B is delivered from the channel 36 through the line 65 to the small cylinder 62. However, since the area of the piston 64 is less than the area of the piston 57, the pump discharge fluid pressure in line 54 will cause pistons 57, 58, 59 and 64 to move to the right to assume the position shown in Fig. 2.

With the pilot valve E in the position as shown in Fig. 2, and the main control valve in the position as shown in Fig. 1, fluid under tank pressure passes upwardly through line 47, port 36b, line 66, valve E and line 67 into the left end cylinder 38 of the main valve D to force the pistons 41, 42, 44 and 45 to the right, as shown in Fig. 2. Due to the right hand movement of the piston 45, fluid contained in its cylinder 38 passes through line 68, pilot valve E, line 69, line 71, to the drain line 15, from which the pressure is increased by the scavenging pump 16 sufficient to replace the fluid in the bottom of the tank B through the check valve 18.

With main valve D, as well as pilot valve E, in the positions as shown in Fig. 2, the pump C operates to draw liquid from the lower end of the hydraulic jack cylinder 1, through port 4, upwardly through line 53, through the intercommunicating ports 34a and 33a of the main control valve D, and into the suction chambers 22 and 23 of the pump. The pump then operates to deliver this fluid from its discharge compartment 24 through the intercommunicating ports 35a and 36a of the main control valve D, line 47 and the normally open port 46 of the shutoff valve F, back into the balancing tank B.

When the piston 2 of the hydraulic jack passes the check valve 6 on its downward stroke, no effect is produced on pilot valve E because check valve 6 does not permit the flow of fluid back into the cylinder 1. When, however, the piston 2 passes port 9 on its downward stroke, pilot valve E is placed in communication (through line 7, check valve 8, cylinder 1, line 13, check valve 14, scavenging pump 16 and check valve 18) with the lower end of the tank B. Concurrently, the right hand end of small piston 64 of

the pilot valve is subjected to tank pressure through the intercommunicating ports 35a and 36b of the main control valve D and through the line 65. Since at this point in the cycle of operation the left end of the piston 57 is only under the influence of substantially atmospheric pressure, the pump pressure on the piston 64 moves it to the left, whereby the pilot valve E assumes its original position as shown in Fig. 1. In this latter position of the system, fluid under tank pressure passes (through line 47, the intercommunicating ports 36a and 36b of the main valve, line 66, the intercommunicating ports 72 and 73 of the pilot valve and line 68) to the right end cylinder 39 of the main valve. Since the left end piston 44 of this valve is now in communication with the drain system (through line 67, the intercommunicating ports 74 and 75 of the pilot valve, line 69 and line 71) the tank pressure on the piston 45 results in moving this piston and its associated pistons to the left to assume their original position as shown in Fig. 1. The system so far described is in condition to repeat the complete cycle of operation as above disclosed.

As already stated, the static load on the polished rod 3 may at times be as high as or greater than 20,000 pounds and, therefore, when due to a breakage in the sucker rod any appreciable portion of this load is lost, the main pump would of course be subjected to an excessive overdrive condition on the upstroke. To safeguard the pump and its associated mechanism against such a contingency, the shutoff valve F is inserted in the line between the tank B and the main valve D, with its main port 46 normally open. The shutoff valve F, as best shown in Fig. 3, comprises a generally S-shaped casing 81, provided at either end with flanged ports 46 and 82, the port 46 being connected with the lower end of tank B and the port 82 with line 47, as shown in Figs. 1 and 2. Formed on one side of the casing 81 is a cylinder 83, the left end of which is closed by a cap 84, forming an internal flange 84a having an internal diameter somewhat less than the diameter of the cylinder 83. The cylinder 83 is provided at its right end with a port 85 communicating with lines 69 and 71, and the left end of the cylinder is connected through a port 86 formed in the cap 84 to a pipe 87 connecting with line 53. In pipe 87 is inserted a three-way valve 88, all as shown in Figs. 1 and 2. Extending through the right end of the cylinder 83 is a piston rod 89, and secured to the left end of this rod is a piston 91 operatively disposed within cylinder 83. Fastened to the right end of the rod 89 is a valve closure member 92 adapted to seal against a seat 93, formed in the outer end of port 46.

The stem 89 is so proportioned with respect to the piston 91 that under normal conditions of operation, the force applied on the head end of the piston 91 is greater than the combined pressures acting on the rod end of the piston 91 and the tank pressure acting on the valve member 92, especially on the rod portion 89 thereof, the resultant force being such as to hold the piston 91 in the extreme right position. Consequently, the valve 92 remains in the open position. If, however, the sucker rod attached to the polished rod 3 breaks and the polished rod is relieved of a portion of its load, there will be a corresponding decrease in the pressure within the jack cylinder 1. Under these abnormal conditions, the reduced pressure under the jack piston and effective upon the head end of the piston 91 is over-

come by the pressure in the balancing tank B acting first upon the rod 89 and, as the valve 92 moves toward closed position and reduces the pressure in the passage around the stem 89, acting finally upon the tank side of the valve 92. This is sufficient to close the shut off valve F during the abnormal upstroke of the jack, and thereby prevent the further passage of fluid from the tank B to the control and pilot valves D and E and to the main pump C. The shut-off valve F will remain closed until the pressures on either side of its closure member 92 have been substantially equalized. In the event of breakage in the sucker rod, this can only be done by dismantling and repairing the deep well pumping equipment.

The valve F can also be closed by turning the three-way valve 88 so that the left end of the cylinder 83 is placed in communication through the valve 88 with the line 71 of the drain system, thereby to reduce the pressure on the left end of the piston 91 substantially to atmospheric pressure. In this connection, the valve F is provided with an auxiliary normally closed by-pass valve 93 disposed in a line 94 connected between the two sides of the closure member 92. To open the shutoff valve F, the three-way valve 88 is turned to its normal position in communication with the jack cylinder 1 and the by-pass valve 93 is turned to its open position so as to equalize the pressure on both sides of the closure member 92. The shutoff valve F will then open, making it possible to put the jack A into operation by starting the pump C.

As a further safety measure, the pump C is provided with a relief valve 29 across its suction and discharge sides to protect the system in the event of any blockage therein.

I claim:

1. A hydraulic pumping jack system comprising: a hydraulic jack cylinder; a piston therein; a balancing pressure tank; a line between said jack cylinder and said tank; a pump disposed in said line; valve means responsive to the operation of said piston for periodically reversing the connections of said pump so as to cause a flow of fluid from said tank to said cylinder on the upstroke of said piston and then from the cylinder to the tank on the downstroke of said piston; a shutoff valve interposed in said line between said tank and said pump; and means responsive to a predetermined pressure difference between said hydraulic jack cylinder and said tank for closing said shutoff valve.

2. A hydraulic pumping jack system comprising: a hydraulic jack cylinder; a piston therein; a balancing pressure tank; a control valve; a line connecting said control valve to said cylinder and to said tank; a pump connected to said control valve, said control valve being effective periodically to reverse the connections of said pump with said line so that fluid from the tank is pumped to the jack cylinder on the upstroke of said piston and on the downstroke of said piston fluid from the jack cylinder is pumped to the tank; a shutoff valve disposed in the line between said tank and said control valve; and means responsive to pressure in said line between said hydraulic jack cylinder and said control valve and to pressure in said line between said tank and said control valve for operating said shutoff valve.

3. A hydraulic pumping jack system comprising: a hydraulic jack cylinder; a piston therein; a balancing pressure tank; a pump; a line between said jack cylinder and said tank; a control

valve for connecting alternately the low pressure side of said pump with said tank and the high pressure side of said pump with said jack cylinder on the upstroke of said piston and then the low pressure side of the pump with the jack cylinder and the high pressure side of the pump with the tank on the downstroke of said piston; means for actuating said control valve in response to the operation of said piston; a shutoff valve disposed in the line between the tank and the pump; means responsive to a predetermined pressure difference between said tank and said hydraulic jack cylinder for closing said shutoff valve; and a relief valve interposed between the low pressure and high pressure sides of said pump.

4. A hydraulic pumping jack system comprising: a hydraulic jack cylinder; a piston therein; a balancing pressure tank; a pump having an inlet and an outlet; valve means responsive to the operation of said piston for controlling flow between said pump, said cylinder, and said tank; conduits connecting said pump inlet and outlet to said valve means; a first line interconnecting said cylinder and said valve means; a second line interconnecting said tank and said valve means; a shutoff valve in said second line; a differential pressure-responsive member for operating said shut-off valve; means for exposing one side of said pressure-responsive member to pressure in said first line; and means for exposing the other side of said pressure-responsive member to pressure in said second line.

5. A hydraulic pumping jack system comprising: a hydraulic jack cylinder; a piston therein; a balancing pressure tank; a pump having an inlet and an outlet; valve means responsive to the operation of said piston for controlling flow between said pump, said cylinder, and said tank; conduits connecting said pump inlet and outlet to said valve means; a first line interconnecting said cylinder and said valve means; a second line

interconnecting said tank and said valve means; a shut-off valve in said second line; a pressure-responsive member having a large diameter portion, an intermediate portion, and a small diameter portion for operating said shutoff valve; means for subjecting said intermediate portion to substantially atmospheric pressure; means for subjecting said large diameter portion to pressure in said first line; and means for subjecting said small diameter portion to pressure in said second line.

6. A hydraulic pumping jack system comprising: a hydraulic jack cylinder; a piston movable therein; a balancing pressure tank; a line between said cylinder and said tank; a pump having an inlet and an outlet; a valve responsive to the position of said piston in said cylinder for connecting said pump outlet to said cylinder and said pump inlet to said tank and vice versa; means responsive to a first pressure and to a second pressure for controlling flow in said line between said tank and said pump; and means for subjecting said controlling means to pressure between said tank and said pump as a first pressure and to pressure between said cylinder and said pump as a second pressure.
